FLASHGUN FOR A PHOTOGRAPHIC CAMERA

James M. Conner, Glendale, Calif., and Bruce K. Johnson,
Andover, Mass., assignors to Polaroid Corporation,
Cambridge, Mass., a corporation of Delaware

Filed Jan. 20, 1967, Ser. No. 5,503

Term of patent 14 years

(Cl. D61—1)

FIG. 1

FIG. 2

FIG. 3

FIG. 4

FIG. 5

FIG. 6

FIG. 7

FIGURE 1 is a front perspective view of a flashgun for a photographic camera showing our new design;

FIG. 2 is a top plan view thereof;

FIG. 3 is a bottom plan view thereof;

FIG. 4 is a side elevational view of one side of the flashgun;

FIG. 5 is a side elevational view of the other side of the flashgun;

FIG. 6 is a front elevational view thereof; and

FIG. 7 is a rear elevational view thereof.

The portions of the device that are diagonally lined are transparent.

We claim:

The ornamental design for a flashgun for a photographic camera, substantially as shown and described.
